Fig. 1.

Fig. 2.

Fig. 3.

A technical drawing of a mechanical assembly, likely a gun barrel or similar component. The drawing shows a central longitudinal axis with various parts attached. Key features include a threaded outer barrel section, a central tube, and a base assembly. Numerous callouts with numbers point to specific parts: 15, 23, 10, 21, 35, 126, 28, 16, 11, 10, 12, and 13. The drawing is done in a clear, technical style with fine lines and cross-hatching for shading.

UNITED STATES PATENT OFFICE.

VERNNA W. GOENS, OF COVERT, KANSAS.

FOLDING CRATE.

1,149,193.

Specification of Letters Patent. Patented Aug. 10, 1915.

Application filed May 4, 1914. Serial No. 836,209.

To all whom it may concern:

Be it known that I, VERNNA W. GOENS, a citizen of the United States, residing at Covert, in the county of Osborne, State of Kansas, have invented certain new and useful Improvements in Folding Crates; and I do hereby declare the following to be a full, clear, and exact description of the invention, such as will enable others skilled in the art to which it appertains to make and use the same.

This invention relates to folding crates.

The object of the invention resides in the provision of a folding crate which can be easily and quickly set up or folded and which will be strong and durable, same being particularly adapted for the transportation of eggs although its use in this respect is in no way restricted to any particular article or product.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a perspective view of the crate set up; Fig. 2, a plan view of the crate with the top broken away; Fig. 3, a section on the line 3—3 of Fig. 2; Fig. 4, a section on the line 4—4 of Fig. 2; Fig. 5, a section on the line 5—5 of Fig. 2; Fig. 6, a view similar to Fig. 5 looking in the opposite direction; Fig. 7, a perspective view of the crate folded, and Fig. 8, a section on the line 8—8 of Fig. 7.

Referring to the drawings the improved crate is shown as comprising a bottom member 10 to the longitudinal edges of which are hingedly connected front and rear members 11 and 12 respectively. Hingedly secured to the free longitudinal edge of the rear member 12 is a top member 13 which carries eye elements 14 for a purpose that will presently appear. Hingedly connected to the ends of the front member 11 are side members 15 and 16 respectively, while eye elements 17 are carried by the front member 11 at the free longitudinal edge thereof. Hinged to the rear member 12 centrally of the latter and extending trans-

versely thereof is a partition 18. Secured across the inner side of the front member 11 is a transverse rod 19 for a purpose that will presently appear. Pivotedly connected to the free edge of the side member 15 are securing arms 20 and 21 and struck from said side member are tongues 22 and 23 with which the arms 20 and 21 are adapted to be engaged to hold said arms against the inner face of said side member. In setting up the crate the arms 20 and 21 are engaged respectively through openings 24 formed in the adjacent end of the rear member 12. After the arms 20 and 21 are engaged through the openings 24 they are then engaged with the tongues 22 and 23. Pivotedly connected to the free edge of the side member 16 are securing arms 25 and 26 and struck from said side member are tongues 27 and 28 with which the arms 25 and 26 are adapted to be engaged to hold said arms against the inner face of said side member. In setting up the crate the arms 25 and 26 are engaged respectively through openings 29 formed in the adjacent end of the rear member 12. After the arms 25 and 26 are engaged through the opening 29 they are then engaged with the tongues 27 and 28. In this manner the bottom, front, rear and side members of the crate are detachably set up as will be obvious.

Pivoted to the free ends of the partition 18 are securing arms 30 and 31 and struck from this partition are tongues 32 and 33 with which the arms 30 and 31 are adapted to be engaged to hold said arms against the partition. In securing the partition 18 in set up position the arms 30 and 31 are engaged between the front member 11 and rod 19 and then engaged with the tongues 32 and 33 respectively. When the crate is in set up position the eye elements 14 and 17 aline and a sealing wire 34 is passed through the eye elements to secure the crate locked.

To fold the crate the sealing wire 34 is first removed and the top member 13 swung to open position. The arms 30 and 31 are then disengaged from the tongues 32 and 33 and from between the front member 11 and the rod 19. The arms 30 and 31 are then engaged against the partition 18 between the latter and the tongues 32 and 33. The partition 18 is then folded against the inner side of the rear member 12. The arms 20, 21, 25 and 26 are then disengaged from respective tongues 22, 23, 27 and 28 and

withdrawn from the openings 24 and 29 respectively after which the arms 20 and 25 are engaged with respective tongues 22 and 27, while the arms 21 and 26 are engaged through openings 35 respectively in the front member 11 and the side members then folded upon the inner side of the front member 11. The bottom member 10 is then folded against the outer side of the front member, the rear member against the inner side of the bottom member and the top against the outer side of the rear member. With the parts thus folded the seal wire 34 is passed through eye elements 17 and 14 to secure the crate in a folded state.

What is claimed is:—

1. A folding crate comprising a bottom member, front and rear members hingedly secured to respective longitudinal edges of the bottom member and said rear member having an opening adjacent each end, a top member hingedly secured to the free longitudinal edge of the rear member, side members hingedly secured to the ends of the front member, securing arms pivoted to the free ends of the side members and detach-

ably engageable through the openings in the rear member from the outer side of the latter, and means for detachably securing said arms against the inner sides of respective side members when said arms are engaged through the openings in the rear member.

2. A folding crate comprising a bottom member, front and rear members, a top member, side members, a partition member hingedly secured to the inner side of the rear member, a rod secured to and extending across the inner side of the front member, securing arms pivoted to the free end of the partition member and detachably engageable between said rod and front member, and means for securing said arms against the partition when same are engaged between the rod and front member.

In testimony whereof, I affix my signature, in the presence of two witnesses.

VERNNA W. GOENS.
